UNITED STATES PATENT OFFICE.

ISIDOR KITSEE, OF PHILADELPHIA, PENNSYLVANIA.

TELEGRAPHIC RELAY.

991,325.

Specification of Letters Patent.

Patented May 2, 1911.

Application filed July 2, 1910. Serial No. 570,140.

To all whom it may concern:

Be it known that I, ISIDOR KITSEE, citizen of the United States, residing at Philadelphia, in the county of Philadelphia and 5 State of Pennsylvania, have invented certain new and useful Improvements in Telegraphic Relays, of which the following is a specification.

My invention relates to an improvement 10 in telegraphic relays and has more special reference to relays adapted to respond to feeble impulses, such for instance as are received on submarine cables.

In my experiments extending over a number 15 of years, I have found that it is greatly advantageous to provide the relay contacts with graphite surfaces. I have experimented with different arrangements and placed the graphite at the tongue of the relay 20 as well as on the stationary contacts and I have found that the arrangement, as is illustrated and described in this specification, is more advantageous than all other arrangements. I have found that a relay, in 25 which the stationary contacts are provided with graphite and the movable contacts are made out of platinum, answers the purpose best where the line has a great capacity and where sticking and sparking would otherwise be present.

The drawing represents in diagrammatic view a preferred form of relay provided with my invention.

In this drawing; 1 is the relay proper; 2 35 is the movable part of contacting tongue of same; 3 the contacts for said tongue. These contacts consist of a metal,—platinum or platinum iridium preferred.

4 and 5 are the stationary contacts. The 40 stationary contact 4 consists of the metallic screw 6 and the graphite 7. This graphite is placed in the hollow of the screw in a manner so as to securely fasten therein. The

stationary contact 5 consists of the metallic screw 9 and the graphite 10. This graphite 45 is secured to the screw in the same manner as the graphite is secured in screw 6.

With such an arrangement and with substantially the relay as illustrated, I have received messages over the Canso-New York 50 cable, the cable having in round numbers 2,000,000 K. R. (capacity multiplied by resistance). The messages were received in Morse characters and translated with the aid of a sounder. In the drawing, this sounder 55 is designated by the numeral 12 and is connected to the polar relay 13 with the interposition of the batteries 14. The polar relay 13 is connected to the line relay with the interposition of the batteries 15 and 16. 60

The cable is designated by the numeral 17.

Having now described my invention, what I claim as new and desire to secure by Letters Patent is:—

1. In a relay, a movable and a stationary contact, one of said contacts consisting of metal and the other of said contacts consisting of graphite.

2. In combination with a telegraphic relay, stationary and movable contacts therefor, the movable contacts comprising a metal, the stationary contacts comprising graphite supported by a metal.

3. A telegraphic relay provided with a tongue, two contacts therefor, the contacts 75 consisting of a metal and also provided with two stationary contacts, each stationary contact provided with a surface consisting of graphite.

In testimony whereof I affix my signature 80 in presence of two witnesses.

ISIDOR KITSEE.
